BABY TRAINING PROTECTOR

Florence O. Breed, $\frac{1}{2}$ Mrs. Edna Brechen, 1420 Roosevelt,
Guymon, Okla.

Filed June 24, 1963, Ser. No. 290,138
1 Claim. (Cl. 4—239)

My invention is directed toward a device for toilet-training baby boys.

It is an object of my invention to provide a new and improved device of the character indicated.

Another object is to provide a new and improved device of the character indicated which prevents undesired spilling of urine during toilet training of baby boys.

Still another object is to provide a new and improved device of the character indicated which can be manufactured easily and inexpensively.

All of the foregoing and still further objects and advantages of my invention will now be explained with reference both to this specification and to the drawings wherein:

FIGURE 1 is a perspective view of my invention adapted for operative use;

FIGURE 2 is a fragmentary plan view of the invention of FIGURE 1;

FIGURE 3 is a cross section through 3—3 of FIGURE 1;

FIGURE 4 is a cross section through 4—4 of FIGURE 3; and

FIGURE 5 is a perspective view of the urine protector as used in FIGURE 1.

Referring now to the drawings, there is shown a toilet chair 10 for infants, the chair having a horizontal seat 12 with an opening 14. Removably positioned below the opening is a chamber pot 16. A urine protector 18 is provided with a vertical member 20 having top and bottom vertically separated horizontal parallel plates 22 and 24 secured thereto. Plate 22 carries a slot 25 which extends inward from the periphery of plate 22 for a short distance. Slot 25 is centrally positioned in plate 22. The vertical separation between plates 22 and 24 is only slightly greater than the thickness of seat 12. The corners of plates 22 and 24 are preferably rounded.

Seat 12 carries a hole 26 adjacent the periphery of opening 14 and filling along a first center line 28 extending from the back to the front of the chair. The protector 18 is installed by fitting plates 22 and 24 on each side of the seat 12 and moving the protector along the periphery of

2

the opening 14 until slot 25 is aligned with hole 26. A screw 30 adapted to fit into hole 26 which is threaded, is then used to hold the protector in place. The screw is installed by hand and is just tight enough to hold the protector securely in place, and the said screw can be removed without using any tools. Consequently, to remove the protector, one merely loosens the screw and removes the protector by a slot 25. When the protector 18 is in place, the bottom end of member 20 extends into pot 16. The surface of member 20 adjacent opening 14 is concave to cause any urine striking same, to flow downward into the pot without spilling elsewhere. The top end of member 20 is closed and curved toward opening 14 to prevent liquid from flowing over the top thereof.

10 The protector can be easily removed for cleaning by loosening the screw 30, so that it can be slid inwardly away from its mounting. Preferably the protector is constructed of metal coated with porcelain or the like. The article must be of sanitary construction because it may have to be scalded if necessary, and therefore plastic construction is not preferred.

15 While I have described my invention with particular reference to the drawings, my protection is to be limited only by the terms of the claim which follows.

20 25 I claim as follows:

In combination with a toilet chair having a horizontal seat having an opening therein and a chamber pot positioned below the opening, said seat having a hole adjacent the periphery of said opening, a urine protector positioned 30 on top of said periphery and extending both downwardly from said seat into said pot and upwardly from said seat, said protector having first and second vertically separated horizontal parallel plates disposed on opposite sides of the seat, the top plate having a slot extending inward from 35 said periphery, said slot being aligned with said hole, and a screw extending through said pot into said hole to hold the protector in position.
